WALTER VILLA GILBERT, OF CAMBRIDGE, ENGLAND.

MEANS FOR CLOSING AND LOCKING PORT-HOLES AND THE LIKE.

1,111,571.

Specification of Letters Patent. Patented Sept. 22, 1914.

Application filed June 13, 1914. Serial No. 844,968.

To all whom it may concern:

Be it known that I, WALTER VILLA GILBERT, a subject of the King of Great Britain and Ireland, and a resident of Cambridge, England, have invented certain new and useful Improvements in Means for Closing and Locking Port-Holes and the like; and I do hereby declare the following to be a full, clear, and exact description of the same.

This invention relates to improvements in means for closing and locking a port hole of a ship or an orifice in any other device (hereinafter for convenience referred to as a port hole in a ship's hull), of the kind comprising a carrier, which may serve as the closing piece, mounted on the ship's hull so as to turn about a hinge pin or equivalent in a plane axially and laterally clear of the port hole; a movable locking member, which may serve as the closing piece, coacting with the carrier and the ship's hull; and means for operating the carrier and the locking member and preferably for controlling the locking member in the open position of the carrier. Said operating means may, for example, comprise a hand lever, a link, and articulations between one end of the link and the lever and between the other end of the link and the locking member, as described in the specification of British Patent No. 9656, dated 20 April 1911, granted to me; or a handle on the locking member; or a handle-provided pinion on the carrier engaging a quadrant on the locking member, or vice versa. Said controlling means may, for example, comprise a stationary guide adapted to be engaged by the locking member to insure the locking member remaining in fixed relation to the carrier, while the carrier is being turned about its hinge pin, and to serve as a stop to the unlocking movement, as described in the specification of British Patent No. 22218 dated 9 October 1911, granted to me. In such means suitable actuation of the operating device, is caused; first, to unlock the locking member, and is caused secondly, to withdraw the closing piece axially from the port hole and to swing the closing piece about its hinge pin laterally clear of the port hole, and reverse actuation of the operating device is caused to restore the parts to their shut position.

The present invention is characterized by means being provided for, at times, operating, or controlling the operation of, one or

a plurality of closing and locking units of the kind aforesaid (hereinafter for convenience generally called closures), from a distant point or otherwise than by manually engaging the lever or levers, or handle or handles, or other operating device, on the spot as hitherto, said means comprising a connecting rod or member (hereinafter for convenience called an "auxiliary" link, although in some cases there is no other link, or called a controlling link,) having connection, at one end, to one of the movable members of the closure and, at the other end, to a movable controlling rod operable from a distant point, the controlling rod, auxiliary link, or one of such connections, being adapted to permit of play or free movement; so that, when the controlling rod is in neutral position, any connected closure may be freely operated by manually engaging its lever, or handle, or other operating device, as hitherto, and without moving the controlling rod, and while the controlling rod is being moved toward another position, it will shut any closure that may be open without acting on any that may be shut, and, when moved to the latter position, will retain each closure shut until the controlling rod is moved to or toward neutral position.

The present invention is further characterized by means being provided so that the closure may be yieldingly held in different open positions without liability of slamming to the shut position or otherwise, in the event of the ship giving a sudden roll or some other cause, and that, in the event of any person having his head through the port hole when the controlling rod is moving to shut the closure, he will be warned by the closure yieldingly coming into contact with his back part, so that by instinct he will at once withdraw his head from the port hole, and the finish of the movement of the controlling rod will unyieldingly shut and lock the closure. If desired, a bell or other audible signal or alarm may be provided and adapted to be automatically set in operation by a projection on the controlling rod or otherwise.

The present invention is further characterized by providing means for adjusting the stationary guide to accommodate, or complementary to the adjustment of other parts to take up slack or lost motion due to

wear on the cam surfaces or other cause, as described in the specification of my application for British Patent No. 8022 dated 5th April 1913.

5 Embodiments of the invention are illustrated by way of example, in the accompanying drawings, in which:—

Figure 1 is a front elevation showing means for operating or controlling the operation of a closure as aforesaid, and showing the latter held shut by the controlling means; Fig. 2 is a plan; Fig. 3 is a plan showing a closure held open and ready to be shut by its hand lever or by the controlling means; Fig. 4 is a section on 4 . . . 4, Fig. 1; Fig. 5 is a section on 5 . . . 5, Fig. 1; Figs. 6, 7 and 8 are front elevations showing three closures respectively open to an obtuse angle, open to an acute angle, and shut; 10 Fig. 9 is a plan of Fig. 6; Figs. 10 and 11 are a front elevation and a side elevation of a modification.

Like reference letters indicate like or equivalent parts wherever repeated in the drawings.

Referring particularly to Figs. 1 to 9, *a* is a port hole in the ship's hull; *b* is a carrier mounted, on the ship's hull or a bed plate, *a*^x, on a hinge pin, *b*¹; *c* is a locking member turnably mounted on the carrier; *c*¹, *c*², are lugs, or the like, on the locking member, *c*, and *a*¹, *a*², are coacting cam or interrupted screw surfaces on the part, *a*^x; *d*, is a lever pivotally mounted, as at *d*¹; *e* is a link connected by articulative means at one end to the lever, as by a biaxial joint as at *f*¹—*f*², and at the other end to a lug, *c*³, on the locking member, *c*, as by a triaxial joint as at *g*¹—*g*²—*g*³. A handle, *x* may be provided 15 on the lever, or on the lever connected end of the link.

h, is a stationary guide consisting of ribs or faces arranged in planes at right angles to and concentric or approximately so with the hinge pin, *b*¹, and adapted to act as a stop to and to engage a projection, *c*³, on the locking member, *c*. The guide may extend in a direction concentric or approximately so with the locking member, *c*, as at *h*¹, so as to maintain or facilitate engagement with the projection *c*³. The carrier has a central glass, *b*⁵, and may have a ring of rubber or other packing, *b*⁶, (Fig. 6), or the packing may be let into the face of the part, *a*^x. The hinge pin, *b*¹, is mounted in a bracket, *b*⁷, which is slotted to permit the carrier to move in a perpendicular direction toward or against the part, *a*^x. The locking member, *c*, may be constructed as a ring surrounding 20 the carrier, and may be held in place by dovetailing, or by single undercut inclined faces, suitable interrupted parts being left in the dovetailing or inclined faces to permit assemblage of the parts.

65 In Figs. 10 and 11, a handle *x*, is placed

on the locking member, *c*, and the hand lever, *d*, link, *e*, and articulations are dispensed with.

According to the present invention, to operate or control the operation of one or a plurality of closures from a distant point as aforesaid, an auxiliary link or member, *k*, may be connected at one end, *k*¹, to the hand lever, *d*, or to a bell cranked extension, *d*^x, thereof (Figs. 1 to 9), and engaged at the other end, *k*², with a controlling rod, *m*, which may be arranged parallel or approximately so to the plane in which the hand lever moves. Other arrangements of the auxiliary link and the controlling rod may be adopted, for instance, in lieu of being connected to the hand lever, the auxiliary link may be connected at one end to the locking member, *c*, (Figs. 10 and 11). Said play or free movement may be provided for by connecting the auxiliary link, *k*, to the controlling rod, *m*, by a slide, *k*³, so as to have facility of sliding thereon and engaging an adjustable or other stop, *m*¹, thereon. The stop *m*¹, allows the closure to be independently operated by the handle, *x*, as hitherto, when the controlling rod is in or is moved to neutral position, *vide* the full line position of the stop, *m*¹ Fig. 3. When the controlling rod is being moved in the opposite direction toward its locking position, the respective stops, *m*¹, *vide* the dotted line position, Fig. 3, engage and operate the respective auxiliary links, *k*, of any port holes which are open, so as to cause the closures to be shut and locked *vide* Figs. 1 and 10 by turning the carriers, *b*, on their hinge pins, and by turning the locking rings, *c*, on their carriers, and remain in engagement, until the controlling rod, *m*, is returned to neutral position, without moving the auxiliary links, *k*, of any shut port holes. It will be understood, however, that said play or free movement may be obtained between the auxiliary link and the lever, or between the auxiliary link and the locking member in analogous manner, for example, by making the auxiliary link of a slotted formation engaging a stud on the cranked end of the lever in a sliding manner, the slot being sufficiently long to accommodate the free movement of the closure by hand, but when the end of the slot engages the stud, to cause the closure to shut. Or, the play may be obtained between the ends of the auxiliary link or member by making it of a compressible, collapsible, flexible, or telescopic nature. In these cases the auxiliary link or member is or may be connected to the controlling rod in a non-slidable manner.

The auxiliary link may be arranged to move in a plane coincident with or parallel to the plane in which the hand lever *d*, moves, *vide* Figs. 1, 6, 7 and 8, and in such a case, if also the controlling rod be parallel to

the plane in which the lever moves, a rigid member, k , with single pivots, k^1 , k^2 , at each end for connecting the auxiliary link to the hand lever and the slide, k^3 , may be employed. In other cases multiaxial joints 5 may be provided to accommodate the movements of the parts, and the slide k^3 , may be adapted to turn on the controlling rod, m , to constitute one of the articulations. In 10 Figs. 10 and 11, a triaxial joint, k^{10} , k^{11} , k^{12} , is employed to connect the auxiliary link to the lug, c^x , on the locking member, and, to accommodate the movements of the parts. The lug is mounted on the locking member 15 by a pivot, c^4 . Further, a biaxial joint, k^2 , k^{13} , is employed to connect the auxiliary link to the controlling rod, m , the slide, k^3 , being adapted to turn on the controlling rod, as aforesaid.

20 A series of auxiliary links are connected to one controlling rod when it is desired to operate or control the operation of a series of closures. The controlling rod may be supported and guided in brackets, m^2 , on the ship's hull or otherwise, and may be articulated or made flexible at parts to accommodate curves or corners in the ship's structure. The controlling rod is adapted 25 to be operated by any suitable motive power, controllable from the bridge or other station on the ship by a lever, valve, switch or the like. For instance, the controlling rod may be connected to a hydraulic ram controlled from the bridge. By these means, 30 the captain may shut any closures that may be open without affecting those which may be already shut, and the passengers or crew may, at normal times, when the controlling rod is in neutral position, open or shut any 35 closure as desired without affecting or deranging the superior control from the bridge.

To yieldingly hold the closure in different open positions, the slide, k^3 , may be provided with a clamping or braking device, 40 comprising a block, k^4 , adapted to bear on the controlling rod, m , and acted on directly or through the intervention of a rubber buffer or spring, k^6 , by a screw, k^6 , all mounted 45 in a boss, k^7 , on the slide, k^3 . The screw, k^6 , is provided with a handle, k^8 , which may be turned through an arc and may have its motion limited by a stop, k^9 , on the boss, k^7 . When the handle, k^8 , is in the full line 50 position (Fig. 1) the friction between the block, k^4 , and the controlling rod is sufficient, under normal conditions, to hold the closure in different open positions and to prevent the closure from slamming under its own 55 weight if the ship rolls. When the handle, k^8 , is in the dotted line position (Fig. 1) the friction is increased to more firmly hold the closure in different open positions, while nevertheless permitting the closure to be 60 operated by hand or by the controlling rod.

To enable physical warning to be given to a person who may have his head through a porthole when the controlling rod commences to move to shut the closure, the stop, m^1 , is so arranged on the controlling rod 70 that, in the neutral position of the latter, the stop is spaced some distance from the slide, k^3 , *vide* the full line position Fig. 3. Thus when the controlling rod is moved to shut the closure, the controlling rod first 75 moves the auxiliary link by the friction of the clamping device, k^4 , so as to cause the carrier, b , to turn on its hinge pin, and, as soon as the passenger feels the closure 80 contact with him, he will instinctively move backward and the clamp will yield to his backward pressure or resistance and allow the closure to be opened thereby sufficiently 85 for him to withdraw his head. The final unyielding shutting and locking of the closure 90 will take place when the stop, m^1 , engages the slide k^3 , *vide* the dotted line position Fig. 3, and *vide* Fig. 2, and causes the carrier, b , to again turn on its hinge pin, and then causes the locking ring, c , to turn on 95 the carrier. It will be obvious that in the case where the play is obtained between the auxiliary link and the lever, or between the auxiliary link and the locking member, an analogous clamping or braking action 100 may be obtained by providing the articulations or sliding connections of the parts with spring washers or equivalent means.

A special stop, p , (Fig. 2,) may be provided on the ship's hull or otherwise to limit 100 the extent of opening of the closure.

To obtain adjustment of the stationary guide as aforesaid, it may be slidably mounted on the hinge pin and located or secured in different positions along the hinge pin 105 by washers, b^2 , surrounding the hinge pin, or by set screws engaging the hinge pin or other part, or by nuts engaging screw threads on the hinge pin or other part, or in 110 analogous manner.

n is a bell having a striker, n^1 , adapted to be sounded by a stop, m^1 , on the controlling rod when it is moved in the direction to shut the closure.

If desired, the controlling rod may be 115 adapted to open the closures. This may be effected, for example, by providing a braking device with which a sufficiently firm clamping action may be obtained, or by providing a second stop, m^x , on the controlling 120 rod on the opposite side of the slide, k^3 , to the stop, m^1 . In the second case, after being operated to open the closures, the controlling rod is moved back so that the stop, m^x , is clear of the slide, k^3 , *vide* Fig. 7, when it 125 is desired to permit the closures to be operated by hand.

What I claim as my invention and desire to secure by Letters Patent is:—

1. Port hole and the like closing means 130

comprising the combination with a closure having a turnable carrier, a movable locking member, and a device for operating the locking member and the carrier on the spot, of a controlling link connected at one end to one of the movable members of the closure, and a movable controlling rod connected to the other end of the controlling link and extending to a distant point, the controlling means being adapted to at times permit of free movement of the closure and at other times to act on the closure so that when the controlling rod is in neutral position the closure may be freely opened and closed by manually engaging its local operating device and without moving the controlling rod, and while the controlling rod is being moved toward another position the controlling rod will shut the closure if it is open but will not act on the closure if it is already shut, substantially as described.

2. Port hole and the like closing means comprising the combination with a closure having a turnable carrier, a movable locking member, and a device for operating the locking member and the carrier on the spot, of a controlling link articulatively connected at one end to one of the movable members of the closure, a movable controlling rod articulatively connected to the other end of the controlling link and extending to a distant point, parts of the controlling means being adapted to at times permit of relative sliding movement, and means for at other times preventing the relative sliding movement, so that when the controlling rod is in neutral position the closure may be freely opened and closed by its local operating device and without moving the controlling rod, and while the controlling rod is being moved toward another position the controlling rod will shut the closure if it is not already shut, substantially as described.

3. Port hole and the like closing means comprising the combination with a closure having a turnable carrier, a movable locking member, and a device for operating the locking member and the carrier on the spot, of a controlling link articulatively connected at one end to one of the movable members of the closure, a movable controlling rod articulatively connected to the other end of the controlling link and permitting the latter at times to have facility of relative sliding movement, and stop means on the controlling rod for at other times engaging the controlling link in different open positions of the closure for moving the latter to the shut position, substantially as described.

4. Port hole and the like closing means comprising the combination with a closure having a turnable carrier, a movable locking member, and a device for operating the locking member and the carrier on the spot, of a

controlling link articulatively connected at one end to one of the movable members of the closure, a slide articulatively connected to the other end of the controlling link, a longitudinally movable controlling rod on which said slide is mounted and is at times adapted to move, and stop means on the controlling rod for engaging the slide in different open positions of the closure for moving the latter to the shut position, substantially as described.

5. Port hole and the like closing means comprising the combination with a closure having a turnable carrier, a movable locking member, and a device for operating the locking member and the carrier on the spot, of a controlling link articulatively connected at one end to one of the movable members of the closure, a movable controlling rod articulatively connected to the other end of the controlling link, the controlling means being adapted to at times permit of free movement of the closure and at other times to act on the closure, and the connection of the controlling link to the controlling rod being adapted to turn in relation to the latter, substantially as described.

6. Port hole and the like closing means comprising the combination with a closure having a turnable carrier, a movable locking member, and a device for operating the locking member and the carrier on the spot, of a controlling link articulatively connected at one end to one of the movable members of the closure, a movable controlling rod articulatively connected to the other end of the controlling link, the controlling means being adapted to at times permit of free movement of the closure, and at other times to shut the closure, and braking means for yieldingly holding the closure in different open positions to prevent it from slamming to the shut position or otherwise, substantially as described.

7. Port hole and the like closing means comprising the combination with a closure having a turnable carrier, a movable locking member, and a device for operating the locking member and the carrier on the spot, of a controlling link articulatively connected at one end to one of the movable members of the closure, a movable controlling rod connected to the other end of the controlling link, parts of the controlling means being adapted to at times permit of relative sliding movement, and clamping means for yieldingly resisting the relative sliding movement, substantially as described.

8. Port hole and the like closing means comprising the combination with a closure having a turnable carrier, a movable locking member, and a device for operating the locking member and the carrier on the spot,

of a controlling link articulatively connected at one end to one of the movable members of the closure, a movable controlling rod articulatively connected to the 5 other end of the controlling link, the controlling means being adapted to at times permit of free movement of the closure and at other times to act on the closure, and adjustable braking means for yieldingly resisting relative movement between parts of the 10 controlling means, substantially as described.

9. Port hole and the like closing means comprising the combination with a closure 15 having a turnable carrier, a movable locking member, and a device for operating the locking member and the carrier on the spot, of a controlling link articulatively connected at one end to one of the movable 20 members of the closure, a movable controlling rod articulatively connected to the other end of the controlling link, yielding means in the connection between the controlling rod and the closure, and unyielding 25 means in such connection, which yielding and unyielding means are adapted to operate in consecutive order when the controlling rod is moved to shut the closure, substantially as described.

30 10. Port hole and the like closing means comprising the combination with a closure having a turnable carrier, a movable locking member, and a device for operating the locking member and the carrier on the spot, 35 of a controlling link articulatively connected at one end to one of the movable members of the closure, a movable controlling rod articulatively connected to the other end of the controlling link and permitting the latter at times to have facility 40 of relative sliding movement, and stop means on the controlling rod for at other times engaging the controlling link for moving the closure to the shut position, the 45 controlling rod when in neutral position having its stop means spaced some distance from the slide, substantially as described.

11. Port hole and the like closing means comprising the combination with a closure 50 having a turnable carrier, a movable locking member, and a device for operating the locking member and the carrier on the spot, of a controlling link articulatively connected at one end to one of the movable members 55 of the closure, a movable controlling rod articulatively connected to the other end of the controlling link and permitting the latter at times to have facility of relative sliding movement, clamping means for yieldingly resisting relative movements of the parts, and stop means on the controlling rod for at other times engaging the controlling link for moving the closure to the 60 shut position, the controlling rod when in

neutral position having its stop means 65 spaced some distance from the slide, substantially as described.

12. Port hole and the like closing means comprising the combination with a closure having a turnable carrier, a movable locking member, and a device for operating the locking member and the carrier on the spot, of a controlling link connected at one end to one of the movable members of the closure, and a movable controlling rod connected to the other end of the controlling link, the controlling means being adapted to at times permit of free movement of the closure and at other times to act on the closure, so that when the controlling rod is 70 in neutral position the closure may be freely opened and closed by manually engaging its local operating device and without moving the controlling rod, and while the controlling rod is being moved toward another position the controlling rod will shut the closure if it is open but will not act on the closure if it is already shut, and when moved to the latter position will retain the closure shut until the controlling rod is 75 moved to or toward neutral position, whether it was previously shut or has just been shut by the controlling means, substantially as described.

13. Port hole and the like closing means 80 comprising the combination with a closure having a turnable carrier and a turnable locking member, of a controlling link connected at one end to one of the turnable members of the closure, and a movable controlling rod connected to the other end of the controlling link and extending to a distant point, the controlling means being adapted to at times permit of free movement of the closure and at other times to act 85 on the closure, substantially as described.

14. Port hole and the like closing means comprising the combination with a closure having a turnable carrier, and a turnable locking member, of a controlling link having one end in operative connection with the carrier, and a slideable controlling rod in operative connection with the other end of the controlling link and extending to a distant point, the controlling means being adapted 100 to at times permit of free movement of the closure and at other times to act on the closure, substantially as described.

15. Port hole and the like closing means comprising the combination with a closure 105 having a turnable carrier, a turnable locking member mounted on the carrier, and a hand lever for operating the carrier and the locking member on the spot, of a controlling link having one end in operative connection 115 with the hand lever, and a slideable controlling rod in operative connection with the other end of the controlling link and ex-

tending to a distant point, the controlling means being adapted to at times permit of free movement of the closure and at other times to act on the closure, substantially as described.

16. Port hole and the like closing means comprising the combination with a closure having a turnable carrier, a turnable locking member mounted on the carrier, a hand lever, and a link articulatively connected to the hand lever and the turnable locking member, of an auxiliary controlling link having one end in operative connection with the hand lever, and a slidable controlling rod 10 in operative connection with the other end of the controlling link and extending to a distant point, the controlling means being adapted to at times permit of free movement of the closure and at other times to act 15 on the closure, substantially as described.

17. Port hole and the like closing means comprising the combination with a closure having a turnable carrier, a turnable locking member mounted on the carrier, and a hand lever for operating the carrier and the locking member on the spot, of a controlling link having one end in operative connection with the hand lever, and a slidable controlling rod in operative connection with the 20 other end of the controlling link and extending to a distant point, the controlling link as well as the controlling rod moving in a plane parallel to the plane in which the hand lever moves, substantially as described.

18. Port hole and the like closing means comprising the combination with a closure having a turnable carrier, a turnable locking member mounted on the carrier, and a hand lever for operating the carrier and the locking member on the spot, of a controlling link, a longitudinally movable controlling rod, a slide on the controlling rod, means for varying the friction of the slide on the controlling rod, stop means on the controlling 45 rod for engaging the slide, and pivotal means connecting the controlling link to the hand lever and to the slide, substantially as described.

19. Port hole and the like closing means comprising the combination with a closure having a turnable carrier, a locking member mounted on the carrier, stationary coacting locking parts, and a hand lever for operating the carrier and the locking member on the spot, of a controlling link, a longitudinally movable controlling rod, a slide on the controlling rod, means for operatively connecting the slide to the controlling rod, and uni-axial joints for connecting the controlling link to the hand lever and to the slide, substantially as described.

20. Port hole and the like closing means comprising the combination with a closure having a turnable carrier, a turnable locking member mounted on the carrier, stationary

coacting locking parts, and a hand lever for operating the carrier and the locking member on the spot, of a bell-crank extension on said hand lever, a controlling link, a longitudinally movable controlling rod, a slide on the controlling rod, means for operatively connecting the slide to the controlling rod, and articulative means for connecting the controlling link to the hand lever and to the slide, substantially as described.

21. Port hole and the like closing means comprising the combination with a closure having a turnable carrier, a turnable locking member mounted on the carrier, a hand lever pivotally mounted on the carrier, and a link 80 articulatively connected to the lever and to the turnable locking member for operating the closure on the spot, of an auxiliary controlling link having one end in operative connection with the hand lever, a longitudinally movable controlling rod, a slide on the controlling rod, means for operatively connecting the slide to the controlling rod, and articulative means for connecting the controlling link to the hand lever and to the 85 slide, substantially as described.

22. Port hole and the like closing means comprising the combination with a closure having a turnable carrier, a movable locking member mounted on the carrier, and stationary coacting locking parts, of a controlling link having one end in operative connection with one of the movable members of the closure, and a slidable controlling rod in operative connection with the 100 other end of the controlling link and extending to a distant point, the controlling means being adapted to at times permit of free movement of the closure and at other times to act on the closure to close it when 105 desired, and to open it when desired, substantially as described.

23. Port hole and the like closing means comprising the combination with a closure having a turnable carrier, a movable locking member mounted on the carrier, and stationary coacting locking parts, of a controlling link having one end in operative connection with one of the movable members of the closure, a slidable controlling 115 rod in operative connection with the other end of the controlling link and extending to a distant point, a slide on the controlling rod, stop means on the controlling rod for operating the slide to shut the closure, and stop means on the controlling rod for operating the slide to open the closure, said stops being so spaced apart as to at times permit of free movement of the closure when desired, substantially as described.

24. Port hole and the like closing means comprising the combination with a closure having a turnable carrier, a turnable locking member mounted on the carrier, stationary coacting locking parts, and means for 130

operating the carrier and the locking member on the spot, of an adjustable stationary guide engaging the turnable locking member, a controlling link having one end in operative connection with one of the turnable members of the closure, and a slidable controlling rod in operative connection with the other end of the controlling link and extending to a distant point, the controlling means being adapted to at times permit of free movement of the closure and at other times to act on the closure, substantially as described.

25. Port hole and the like closing means comprising the combination with a closure having a turnable carrier, a turnable locking member mounted on the carrier, and means for operating the carrier and the locking member on the spot, of a controlling link having one end in operative connection with the locking member, and a slidable controlling rod in operative connection with the other end of the controlling link and extending to a distant point, the controlling means being adapted to at times permit of free movement of the closure and at other times to act on the closure, substantially as described.

26. Port hole and the like closing means comprising the combination with a plurality of closures each having a turnable carrier, a turnable locking member mounted on the carrier, and means for operating the carrier and the locking member on the spot, of a plurality of controlling links one for each closure and respectively having one end in

operative connection with one of the movable members of its respective closure, and a slidable controlling rod in operative connection with the other end of each respective controlling link, the controlling means being adapted to at times permit of free movement of all the closures and at other times to act on all the closures, substantially as described.

27. Port hole and the like closing means comprising the combination with a plurality of closures each having a turnable carrier, a turnable locking member mounted on the carrier, and means for operating the carrier and the locking member on the spot, of a plurality of controlling links one for each closure, a slidable controlling rod in operative connection with the other end of each respective controlling link, and means for varying the friction at the respective operative connections, the controlling means being adapted to at times permit of free independent movement of any of the closures by manually engaging the local operating means, and at other times to act on any of the closures to hold them in different open positions, to shut any of the closures without operating those which are already shut, and to hold all the closures shut, substantially as described.

In testimony whereof I affix my signature, in presence of two subscribing witnesses.

WALTER VILLA GILBERT.
